Fig. 1.

Fig. 2.

Fig. 3.

FIG. 1 is a front elevational view of a laboratory fume hood, showing my new design;

FIG. 2 is a side elevational view thereof;

FIG. 3 is a rear elevational view thereof; and

FIG. 4 is a top plan view of a laboratory fume hood.

The side opposite to that shown in FIG. 2 is the same in appearance as that shown in FIG. 2.

The dominant features of my design reside in those portions shown in full lines.

I claim:

The ornamental design for a laboratory fume hood, as shown and described.
